EDWARD S. KLAUSNER, OF OWEGO, NEW YORK.

FITTING-UP BOLT DEVICE.

Application filed June 12, 1925. Serial No. 36,604

- This invention relates to fitting-up bolts used for temporarily holding together in proper relation plates or parts of structural iron and steel work preparatory to riveting.
- 5 An object of the invention is to provide a fitting-up bolt device which overcomes the drawbacks of ordinary fitting-up bolts, such as the time and labor required in unscrewing the nuts, and the difficulty of withdrawing the
- 10 screw-threads of the bolts through the openings in the parts, which may be out of line.
- 15 A further object is to provide a very inexpensive and indefinitely reusable fitting-up device which employs a slotted block straddling a neck of an unthreaded part of the bolt, and which is so constructed that the block can be disengaged readily and very quickly.

In the accompanying drawings, forming 20 a part hereof:

Fig. 1 is an elevation of the assembled device, showing structural members in section;

Fig. 2 is a similar view looking at right angles to Fig. 1;

25 Figs. 3 and 4 are cross-sections taken respectively on the lines 3-3 and 4-4 of Fig. 2;

Figs. 5, 6 and 7 are end, side and plan views of the block; and

30 Figs. 8 and 9 are two elevations, looking at right angles to each other, of the forward portion of the bolt.

The bolt 1 has a screw-threaded portion 2, which may be termed the rear portion. The 35 major portion of the bolt, which is passed through the rivet holes in the structural parts *a*, *a*, is unthreaded, and further to facilitate the insertion of the bolt its forward end 3 is tapered. A nut 4 is placed on the screw-threaded portion of the bolt, for tightening 40 the device.

The forward part of the bolt, in the basal portion of the tapered end, is recessed at opposite sides to form a neck 5, having flat sides 45 6. These sides are reversely inclined in cross-section so that the neck varies in width substantially from one end of the cross-section to the other, as seen in Fig. 3. The outer shoulders 7 of the neck likewise slope in the 50 direction of their length, the slope being inward, that is to say, away from the point of the bolt, in the direction proceeding from the thinner end of the neck cross-section to the thicker end. The inner shoulders 8 extend 55 at right angles to the length of the bolt, and may be sloped transversely of the bolt.

The part 9 is a rigid block having a slot 10 to pass over the neck and between the shoulders, the sides of this slot being reversely inclined to correspond to the cross-section of 60 the neck, the sides of the slot diverging from the narrowest width at the closed or rear end of the slot to the widest region, which is at the open, or forward, end of the slot. The block, furthermore, has a top or outer face 11 which 65 slopes downward, or inward, from the rear end to the front end of the block, similarly to the slope of the shoulders 7.

The under surface of the block is straight and flat in order to give an equal and flat 70 bearing on the surface of the steel, and to keep the block from creeping when strained.

The bolt having the nut thereon is inserted through the holes in the parts *a*, *a*, the nut being adjusted so that the neck 5 of the bolt projects at the other side of the structure from the nut. The block 9 is then placed transversely over the necked portion of the bolt, the wide end of the slot in the block and the narrow end of the thickness of the block being 75 in advance, and passing first over the narrow end of the neck and under the high end of the shoulders 7. The block having been loosely seated, the nut 4 is quickly tightened.

When one or more of the rivets have been 80 driven, the parts *a*, *a* are drawn together, and the block 9, by reason of the construction which has been described, can then be taken out by hand, or by a quick blow of the hammer, and it is not necessary to stop to unscrew or loosen the nut. The bolt is then 85 withdrawn or driven out easily and without injury, as there is no resistance due to screw-threads catching in the holes; and a rivet is driven in its place.

90 It will be understood that the block of this device is not a wedge, the tightening being obtained by a nut. It is rather in the nature of a loose retaining collar, which is held tight with the rest of the device by the 95 nut. When the strain is relieved by the driving of the rivets it may sometimes be picked out by hand. There may be some residual strain, however, holding the block after the rivets have been driven. Likewise, after repeated use there is likely to be some distortion in the block or possibly in the bolt, and as the parts are made by casting the surfaces 100 will not be perfectly smooth. If for any reason the block should stick, it can be quickly dislodged by a tap of a hammer on the bifurcated forward end. It will be observed 105 110

that the inclinations of the cooperative surfaces 7 and 11 of the shoulders and the top of the block, and of the other cooperative surfaces constituting the sides of the slot 10 5 and the sides 6 of the neck, are such that as soon as there is any rearward movement of the block there is a separation between these surfaces, and for every degree of such movement there is a corresponding increase 10 in separation. Consequently the block comes loose at once, and time will not be lost owing to persistent sticking, even though the parts be somewhat roughly made, and even though there may be some distortion as explained. 15 For a practical reason it is important that the design of the device be such that it may be made by casting, rather than by machining, which would make the cost prohibitively high. My device can be made very cheaply 20 and advantageously of malleable cast-iron, which has adequate strength but is somewhat bendable. When the block has been hammered a good many times on the ends of its bifurcations, these ends may become somewhat 25 bent or upset, but they are so widely spaced owing to the divergence of the inner sides of the slots that the block will not bind seriously when it is removed. The plan of the device is one in which the block be- 30 comes, so to speak, both lower and wider with respect to the shouldered neck of the bolt when it is displaced rearward.

In the fabrication of structural parts, speed is of the essence, and the practically instantaneous removability of this fitting-up device 35 makes possible a very substantial saving in

such manufacturing. Other advantages are the extremely low first cost of the devices, the capacity for indefinite reuse, the perfect interchangeability of the bolts and blocks, 40 and the security with which the device temporarily holds the parts to be riveted.

While the preferred form of the invention has been described, I do not wish to limit myself to the precise details. 45

What I claim as new is:

A fitting-up bolt device, comprising a bolt threaded at one end and tapered at the opposite end, the base of the tapered end portion being recessed to receive a wedge key, 50 the recesses being in opposite sides of the bolt with their vertical walls formed of planes, lines lying in said planes and in a plane passing through the axis of the bolt being parallel to each other, said walls being 55 relatively divergent in horizontal plane, the upper walls of the recesses inclining in the direction of divergence of the vertical walls, and the lower walls being convergent with the upper walls and inclined downwardly 60 and outwardly from the vertical walls, and a wedge key having divergent leg portions and their upper surfaces inclined downwardly in the direction of leg divergence, the lower 65 surfaces of the legs being parallel to the horizontal plane of the key, whereby the divergent leg portions and inclined upper surfaces wedgingly cooperate with the similar vertical and upper walls of the recesses, while the horizontal lower surfaces of the legs bear 70 on the plates with which the bolt cooperates.

EDWARD S. KLAUSNER.
